UNITED STATES PATENT OFFICE.

CHESTER E. WARNER, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PULL-SWITCH SOCKET.

Application filed September 7, 1920, Serial No. 408,580. Renewed November 27, 1925.

My invention relates to circuit controlling devices, and particularly to pull switch sockets and switch mechanism for such sockets.

One of the objects of my invention is to provide a pull switch socket which will be efficient and durable in use, simple in construction and cheap to manufacture.

A further object of my invention is to provide a pull switch socket having a switch mechanism, which is capable of handling currents of large wattage. Such sockets are now called upon to carry current for electric flat irons, vacuum cleaners, and other devices taking more current than the sockets commonly in use are capable of handling, and in view of the limited space available in the ordinary socket it has been a matter of great difficulty to produce a pull switch mechanism which could be safely employed in a socket of the present type. This is accomplished in the socket and switch mechanism forming the subject matter of the present invention.

Further objects will appear from the detailed description to follow and from the appended claims.

In the drawings in which two embodiments of my invention are shown:

Fig. 1 is a top plan view of a pull switch angle socket;

Fig. 2 is a section on the line 2—2 of Fig. 1;

Fig. 3 is a section on the line 3—3 of Fig. 2;

Fig. 4 is a section on the line 4—4 of Fig. 3;

Fig. 5 is a section on the line 5—5 of Fig. 2;

Fig. 6 is a disassociated perspective view of part of the switch mechanism;

Fig. 7 is a perspective view of a combined wiring terminal and switch contact;

Fig. 8 is a perspective view of the switch frame;

Fig. 9 is a section substantially on the line 9—9 of Fig. 10 of a straight pull switch socket;

Fig. 10 is a side elevational view of the socket with the casing broken away;

Fig. 11 is a bottom plan view of the interior socket construction;

Fig. 12 is a top plan view of the interior socket construction;

Fig. 13 is a section on the line 13—13 of Fig. 9; and

Fig. 14 is a perspective view of the switch frame.

Referring now to Figs. 1 to 8 inclusive, the pull switch angle socket shown therein comprises a threaded shell contact 20, a center contact 21, a wiring terminal 22, for the shell contact 20, a wiring terminal 23 for the center contact 21, a switch mechanism 24 for controlling the circuit between the center contact 21 and its wiring terminal 23, a one-piece insulating base 25 for supporting the shell contact 20, the center contact 21, the wiring terminals 22 and 23, and the switch mechanism 24, and a sheet metal casing 26 surrounding the insulating base 25, and threaded shell contact 20.

The threaded contact 20 is always electrically connected with its wiring terminal 22 by means of a screw 27 (Figs. 1 and 3) which extends through registering openings in the flange 28 of the threaded shell contact and the insulating base 25 and is threaded into the binding plate 29 of the wiring terminal 22.

The switch mechanism 24 controls the circuit between two stationary switch contact members 30 and 31 (Figs. 1 and 4), the contact member 30 being always electrically connected with the center contact 21 by means of a tubular metal eyelet 32, and the contact member 31 being formed as part of an integral sheet metal stamping 33, (Fig. 7), this stamping being formed to provide, in addition to the contact member 31, a binding plate portion 34, for the binding screw 35 for the wiring terminal 23, and a conducting strap portion 35 for electrically connecting the binding plate portion 34 with the switch contact 31.

One of the switch contacts 31 is thus always electrically connected with the wiring terminal 23 and the other switch contact 30 is always electrically connected with the center contact 21 by means of the tubular metal eyelet 32. This tubular eyelet 32 not only serves to electrically connect the contact 30 and the center contact 21 but also serves to hold the parts in position on the insulating base. The stamping 33 is held in place on the insulating base by means of a screw 36 (Fig. 4) threaded into the base portion of the stamping 33.

The switch mechanism 24 comprises in addition to the switch contacts 30 and 31, a pivoted oscillatable switch blade 37, for

making and breaking the electrical connection between the contacts 30 and 31, an S-shaped bent wire spring 38 (Fig. 6) bearing on the switch blade 37 and shift-
 5 able back and forth past a dead center to cause oscillation of the switch blade 37, a U-shaped connecting link 39, pivotally connected to one end of the S-shaped spring 38, a combined crank shaft 10 and pivot pin member 40 pivotally connected with the connecting link 39 for driving it, a driven ratchet member 41 secured to drive the crank shaft 40, a combined lever and driving ratchet member 42, os-
 15 cillatably mounted on the pivot pin 40 for driving the ratchet member 41, a pull chain 43 secured to the lever member 42, a pivot pin 44 on which the blade 37 is oscillatably mounted and a sheet metal switch frame 20 45 (Fig. 8) for supporting the pivot pin 44, crank shaft and pivot member 40 and other parts of the switch mechanism.

The oscillatable switch blade 37 comprises an insulating member 46, which may be of sheet fibre, pivotally mounted on the pivot pin 44, and a contact member 47 for controlling the circuit between the switch contact members 30 and 31. This contact member 47 may be a sheet metal stamping, strad-
 25 dling the insulating member 46 and having a pair of opposed projections or lugs 48 ex-
 30 tending into a notch in the upper edge of the insulating member 46, the lower portion of the contact 47 having an opening to re-
 35 ceive an extending lug 49 upon the insulat-
 ing member 46, the projection 48 and the lug 49 serving to position the contact mem-
 ber 47 and hold it in place on the insulating member 46. This manner of supporting the
 40 contact member 47 permits it to yield slightly and to adjust itself to the switch contact members 30 and 31 in operation.

For limiting the oscillating movement of the insulating member 46, the switch frame 45 is provided with a laterally extending integral projection 50 (Fig. 8), which in one position of the insulating member 46 engages a shoulder 51 on the insulating member 46, and in another position engages a shoulder portion 52 on the insulating member 46. This prevents the entire shock of the switch blade from coming onto the contact members 47, 30 and 31.

The S-shaped bent wire spring 38 strad-
 55 dles the insulating switch blade 46 and has a transversely extending pivot portion 53, for engaging a pivot notch 54 in the switch blade member 46. The ends of the bent wire spring 53 are bent outwardly to provide pivot portions 55 which extend into openings 56 in the side arms of the U-shaped connecting link 39 to pivotally connect the link 39 with the bent wire spring 38.

The upper end of the U-shaped connect-
 60 ing link 39 is provided with a pair of open-

ings 57 through which the crank pin por-
 70 tion 58 of the crank shaft member 40 extends. The crank shaft member 40 may be formed of a piece of wire of uniform thickness, formed into the shape shown in Fig. 6, to provide a circular disc portion 59, from which the crank pin 58 extends, and a flat-
 75 tened portion 60 for engagement with a slot 61 in the driven ratchet member 41, whereby the crank shaft member 40 is caused to rotate with the driven ratchet member 41.

The driven ratchet member 41 may be formed of a sheet metal stamping, shaped to provide a cup-shaped journal portion 62, which has a bearing in an opening 63, formed in the bracket portion 64 of the switch frame 45. The end of the crank shaft 40 has a bearing in an opening 65, formed in the bracket member 66 of the switch frame 45, the crank shaft member 40 being thus supported for rotation in the bearing openings 63 and 65. The bracket 80 64 also has a bearing opening 66^a to receive the end of the pivot pin 44 on which the switch blade 37 is mounted.

The combined driving ratchet member and switch lever 42 is provided with a pair of ratchet teeth 67, which engage corresponding ratchet openings 68 in the driven ratchet member 41. The member 42 is pro-
 95 vided with a chain rail portion 68 for receiving the pull chain 43, the pull chain be-
 100 ing held in place between this chain rail por-
 tion and the outer portion of the driven ratchet member 41.

For returning the switch lever 42 after it has been operated by the pull chain 43 and for holding the driving ratchet member 42 over against the driven ratchet 41 to cause the ratchet teeth 67 to engage the ratchet opening 68, a coil torsion and compression spring 69 is provided, one end of which is secured to a lug 70 on the switch lever 42, and the other end of which is secured to the switch frame 45. The spring 69 is un-
 110 der a compression so that it tends to force the driving ratchet 42 over against the driven ratchet member 41, to cause the ratchet teeth 67 to engage the ratchet open-
 115 ings 68.

The connecting link 39 bears against and is supported by the pivot pin 44, on which the switch blade 37 is mounted, and the crank shaft 40 in its movement swings the spring 38 past a dead center, to cause a quick movement of the switch blade 37. Each pull upon the pull chain 43 moves the driven ratchet member 41 180 degrees and also causes the crank pin 58 to move 180 degrees. This movement of the crank pin 58 through 180 degrees shifts the pivotal point of connection between the connecting link 39 and the spring 38 at 55 past the dead center line between the pivot portion 53 of the spring and the pivot pin 44 of the 120
 125 130

switch blade, and causes a quick movement of the switch blade 37 to make or break the circuit between the contacts 30 and 31. The ends of the crank shaft 40 may be pinched together to flatten them, as indicated at 71 and 72, to hold the parts in their assembled position. For limiting the return movement of the switch lever 68 under the action of the portion spring 69, the switch frame 10 45 is provided with a stop projection 73 which is engaged by the hook portion 74 of the chain rail 68 on the return movement of the chain rail.

In the straight pull switch socket shown 15 in Figs. 9 to 14 inclusive, the switch mechanism may be the same as in the form just described, with the exception of the switch frame, the similar parts including the switch blade 37, the S-shaped spring 38, the connecting link 39, the crank shaft and pivot pin member 40, the driven ratchet 41, the combined driving ratchet and switch lever member 42, the pull chain 43, the pivot pin 44, and the coil spring 69. In the straight 20 25 socket, however, the switch mechanism is mounted between two insulating base parts 76 and 77, and the switch blade 37 oscillates in a horizontal plane transverse to the axis of the sockets.

30 The threaded shell socket 78 is always electrically connected with its wiring terminal 79 by means of the screw 80, which also holds the wiring terminal 79 and the threaded shell contact 78 in place on the insulating base part 77. The upper insulating base part 76 is secured to the wiring terminal 79 by means of a screw 81 (Figs. 9 and 10).

The switch blade 37 controls the circuit between the center contact 82 and its wiring terminal 83, by controlling the circuit between the two switch contacts 83 and 40 45 50 84 (Fig. 13). The contact 83 is always electrically connected with the center contact 82 by means of a tubular metal eyelet 85. The binding plate portion 86 of the wiring terminal 82 is clamped against the contact finger 84 by means of a screw 87 (Fig. 13), which also holds the contact 84 and binding plate portion 86 in position with respect to the upper insulating base 76.

The switch frame 75 (Fig. 14) has a bracket portion 88 having a bearing opening 89, to receive the journal portion 62 of the driven ratchet member 41.

55 For limiting the movement of the switch blade 37, a projection 90 is provided, extending laterally from the switch frame 75, in position to be engaged by the shoulder portions 91 and 92 of the switch lever 37, to limit the oscillatory movement of the switch lever. A stop projection 93 is provided to limit the return movement of the driving ratchet member 42 under the action of the return spring 69. A bearing opening 94 is provided in a bracket portion 95

of the switch frame for the axial portion of the crank shaft member 40. A bearing opening 96 is provided in the switch frame for one end of the pivot pin 44, on which the switch blade 37 is oscillatably mounted. 70 An opening 97 is provided in the switch frame 75 for the passage of the pull chain 43, which extends laterally from the socket to the guide member or horn 98.

The operation of this switch mechanism 75 is the same as that of the form previously described.

While I have shown but two embodiments of my invention, it may be embodied in other forms, covered and defined by the appended claims.

Having thus described my invention, what I claim as new and desire to secure by Letters Patent of the United States is:

1. A switch mechanism comprising a pivoted switch blade, oscillatable back and forth, a spring bearing on said switch blade, and shiftable back and forth past a dead center to cause oscillation of said switch blade, and means for shifting said spring, 65 comprising a link having one end connected with the spring and a crank connected to the other end of the link, and a support with which said link has a sliding engagement. 95

2. A switch mechanism comprising a pivot pin, a switch blade pivoted on said pivot pin and oscillatable back and forth, a spring bearing on said switch blade and shiftable back and forth past a dead center to cause oscillation of said switch blade, and means for shifting said spring comprising a link having one end connected with the spring and slidably engaging said pivot pin, and a crank connected to the other end of 100 105 the link.

3. A switch mechanism comprising a pivot pin, a switch blade pivoted on said pivot pin and oscillatable back and forth, a spring bearing on said switch blade and shiftable back and forth past a dead center to cause oscillation of said switch blade, and means for shifting said spring comprising a link having one end connected with the spring and slidably engaging said pivot 110 115 pin.

4. A switch mechanism comprising a pivot pin, a switch blade pivoted on said pivot pin and oscillatable back and forth, a spring bearing on said switch blade and shiftable back and forth past a dead center to cause oscillation of said switch blade, and means for shifting said spring comprising a link having one end connected with the spring and slidably engaging said pivot pin, 120 125 and a rotatable member for actuating said link.

5. A switch mechanism comprising a pivoted switch blade oscillatable back and forth, a compression spring bearing on said 130

switch blade and shiftable back and forth past a dead center to cause oscillation of said switch blade, and means for shifting said spring comprising a link straddling 5 said switch blade and having one end connected with said spring and a crank connected to the other end of the link.

6. A switch mechanism comprising a pivoted switch blade, oscillatable back and forth, a wire compression spring bearing on said switch blade, and straddling said blade, and shiftable back and forth past a dead center to cause oscillation of said switch blade, and means for shifting said 10 spring comprising a link straddling said switch blade and having one end connected with the spring, and a crank connected with the other end of said link.

7. A switch mechanism comprising a 20 pivot pin, a switch blade pivoted on said pivot pin and oscillatable back and forth, a spring bearing on said switch blade and shiftable back and forth past a dead center to cause oscillation of said switch blade, and means for shifting said 25 spring comprising a link straddling said switch blade and slidably engaging said pivot pin, and having one end connected with said spring, and a crank connected to the other end of 30 said link.

8. A switch mechanism comprising a pivot pin, a switch blade pivoted on said pivot pin and oscillatable back and forth, a compression spring bearing on said switch 35 blade and shiftable back and forth past a dead center to cause oscillation of said switch blade, and means for shifting said spring comprising a link straddling said switch blade and slidably engaging said 40 pivot pin, and having one end connected with said spring.

9. A switch mechanism comprising a pivoted switch blade, oscillatable back and forth, an S-shaped compression spring bearing 45 on said switch blade and shiftable back and forth past a dead center to cause oscillation of said switch blade, and means for shifting said spring comprising a link having one end connected with said spring, and 50 a crank connected to the other end of the link.

10. A switch mechanism comprising a pivoted switch, oscillatable back and forth, an S-shaped compression spring bearing on 55 said switch blade, and having one end pivotally connected with said switch blade, and shiftable back and forth past a dead center to cause oscillation of said switch blade, and means for shifting said spring comprising a 60 link having one end pivotally connected with the other end of said S-shaped spring and a crank connected to the other end of said link.

11. A switch mechanism comprising a 65 pivoted switch blade, oscillatable back and

forth, a compression spring bearing on said switch blade and shiftable back and forth, past a dead center to cause oscillation of said switch blade, said spring being formed of bent wire and comprising two U-shaped portions straddling said switch blade, and two pivot pin portions extending outwardly from 70 said U-shaped portions, and means for shifting said spring comprising a U-shaped link having openings therein to receive said pivot 75 pin portions.

12. A switch mechanism comprising a switch blade having an oscillatably mounted insulating member, and a contact member straddling said insulating member, said insulating member having a notch therein, and the ends of said contact member having lugs extending into said notch, said insulating 80 member having a projection thereon, said contact member having an opening 85 therein into which said projection extends.

13. A switch mechanism comprising a pivoted switch blade oscillatable back and forth, a compression spring bearing on said switch blade and shiftable back and forth past a dead center to cause oscillation of 90 said switch blade, and means for shifting said spring, said spring comprising an integral bent member having two S-shaped portions 95 one on each side of said switch blade.

14. A switch mechanism comprising a pivot pin, a switch blade pivoted on said pivot pin and oscillatable back and forth, a spring bearing on said switch blade and shiftable back and forth past a dead center to cause oscillation of said switch blade, and means for shifting said spring comprising a link having one end connected with the 100 spring and slidably engaging said pivot pin, and means connected to the other end of the link for actuating it.

15. A switch construction comprising an oscillatable switch blade, a switch frame having a large bearing opening and a small bearing opening, a crank shaft having a large journal in said large bearing opening and a small journal in said small bearing opening, a crank pin extending from one side of said large journal and transmission from said crank pin to said switch blade. 110

16. A switch construction comprising an oscillatable switch blade, a switch frame having a large bearing opening and a small bearing opening, a crank shaft having a large journal in said large bearing opening and the small journal in said small bearing opening, a crank pin extending from one side of said large journal and transmission from said crank pin to said switch blade, a 120 boss extending from the other side of said large journal, and a ratchet member engaging said boss for rotating said crank shaft. 125

In witness whereof, I have hereunto subscribed my name.

CHESTER E. WARNER.
